James E. Cupp

UNITED STATES PATENT OFFICE

172,784

MULTIFACED ENGINEERING SCALE OR SIMILAR ARTICLE

James E. Cupp, San Diego, Calif.

Application September 28, 1953, Serial No. 26,980

Term of patent 14 years

(Cl. D52—1)

To all whom it may concern:

Be it known that I, James E. Cupp, a citizen of the United States, residing at San Diego, State of California, have invented a new, original, and ornamental Design for a Multifaced Engineering Scale or Similar Article, of which the following is a specification, reference being had to the accompanying drawing, forming a part hereof.

Fig. 1 is a top plan view of a multifaced engineering scale or similar article, showing my new design;

Fig. 2 is a perspective view thereof; and

Fig. 3 is an end elevational view.

I claim:

The ornamental design for a multifaced engineering scale or similar article, as shown.
